UNITED STATES PATENT OFFICE.

GEORGE WHITMAN McMULLEN, OF CHICAGO, ILLINOIS.

SUGAR-PRODUCING PRODUCT.

No. 898,592.

Specification of Letters Patent. Patented Sept. 15, 1908.

Application filed July 22, 1907. Serial No. 384,970.

To all whom it may concern:

Be it known that I, GEORGE WHITMAN McMULLEN, a citizen of the United States, residing at Chicago, in the county of Cook 5 and State of Illinois, have invented or discovered a new and useful Sugar-Producing Product as an Article of Manufacture, of which the following is a specification.

This invention relates to a new and useful 10 sugar producing product, and the salient objects of the invention are to provide a product which facilitates and economizes the production of sugar; minimizes the loss, and therefore affords a larger yield from a given 15 quantity of material, and renders practicable and economical the saving of a valuable by product incident to the recovery of sugar from the main product.

The invention consists in the matters hereinafter described and particularly pointed out in the appended claims.

I have discovered that sugar producing plants, notably the sugar beet, may be so treated as to greatly facilitate and economize 25 the recovery of the sugar therefrom by reducing the beets to a desiccated and finely comminuted condition before attempting the extraction of the sugar contents.

I am aware that it has been suggested that 30 sugar beets might be sliced up, the slices dried and thereafter the sugar extracted by saturation and diffusion. So far as I am aware this suggestion has never been carried into practical effect, but however this may 35 be, the improved product described herein is characteristically new and useful.

In producing the product of the present invention, I take the green beets, preferably as promptly as practicable after they have 40 been harvested, so as to avoid to the greatest practicable extent deterioration and chemical change, and after suitably cleansing the beets, reduce the same to slices or relatively small bodies preparatory to drying the same.

45 It is important that the beets should be sliced or cut as distinguished from mashing or grinding, for reasons well understood by those skilled in the beet sugar art. I next desiccate the cut up beets, and so far as my 50 present knowledge is concerned this must be accomplished under carefully controlled conditions and in a peculiar manner if the full, or practically the full, crystallizable, or non-inverted, sugar content is to be preserved 55 without inversion or loss, in the desiccated material. This drying step may be practi-

cally carried out substantially as follows: I place the sliced or cut up beets, in a considerably distributed or spread out condition, in a substantially closed chamber wherein the material is subjected to a moderate but continued evaporating temperature, but maintain the interior of the chamber as nearly free from or devoid of distinct currents of air as practicable, so that the material being desiccated is constantly enveloped by the moisture expelled therefrom. This moisture is continuously removed by creating and maintaining a relatively low vapor pressure in a part of the chamber away from that part of the chamber wherein the material is supported. By suitably arranging the apparatus and material, I induce a constant vapor flow from the localities of higher vapor pressure, *i. e.* that part of the chamber wherein the material is supported, to that part of the chamber wherein the lower vapor pressure obtains, and there condense and precipitate the vapor continuously. It is to be noted that this vapor flow from the regions of relatively high to the regions of relatively low vapor pressure is independent from and as far as practicable unaccompanied by a corresponding bodily flow or current of air.

That is to say, the air within the chamber is maintained as nearly practicable dead air. It is important that in so desiccating, the temperature be controlled so as to remain approximately uniform in that part of the chamber wherein the product is supported and that it should not rise high enough to effect any substantial chemical change in the saccharine constituents of the material under treatment. Practically I have determined that the temperature should be kept in the vicinity of 155 degrees Fahrenheit, but it is probable that a temperature somewhat higher would not be dangerous, especially if not maintained at such higher temperature for too long a period. On the other hand, the rate of evaporation and the economy of evaporation is to a considerable extent proportional to the temperature, and it is therefore desirable to maintain the temperature as high as permissible without subjecting the material to danger of deterioration. I have demonstrated that desiccation may be successfully and fairly rapidly effected at temperatures considerably lower than that above specified by pursuing the method described.

105 It will be understood that the condensation of the moisture expelled from the beets will

be effected by bringing the vapor into contact with suitable relatively cold condensing apparatus,—preferably surface condensers.

Having desiccated the product, I next reduce the same to finely comminuted, *i. e.* granulated or pulverulent, form. This comminution may be effected at any desired time after the desiccation, either immediately or at some future period. The desiccated cos-
10 settes keep perfectly for any reasonable length of time, if kept reasonably dry.

In reducing the dried cossettes to comminuted form, I use any suitable grinding or granulating machine, and in comminuting the material I endeavor to avoid as far as practicable reducing the material to an impalpable powder. In its preferred condition of comminution, the product may be aptly described as being in the form of meal.

20 It is the object of my invention to desiccate the material to a condition which will prevent fermentation or molding under all ordinary exposures. Under varying climatic conditions, the degree of desiccation 25 may be safely varied within reasonable limits. In practice I prefer to dry until the content of moisture is well below twenty percent of the weight of the desiccated product, but undoubtedly in some climates it may 30 safely contain a somewhat higher percentage of moisture.

I have demonstrated that the crystallizable sugar content contained in the beets in their fresh state when harvested, is fully preserved and retained in undeteriorated condition in this desiccated beet meal. I have

also demonstrated that the recovery of the sugar therefrom by diffusion may be accomplished much more rapidly than when treating the green or undesiccated material; that the percentage of purity is fully as high and usually higher than with the green product; that the number of diffusion battery units required to effect substantially complete extraction is less than that required for the green product and that the exhausted or extracted meal may be dried either by expressing or by draining and evaporating at such a pronounced economy as to make of it a valuable commercial by product. Moreover, this exhausted meal is in ideal condition for conversion into animal food.

I claim as my invention:

1. As a new article of manufacture, sugar producing plant, dried, containing less than 30% moisture, comminuted, adapted for indefinite preservation without deterioration, and containing practically the same amount of uninverted sugar as before being dried, substantially as described.

2. As a new article of manufacture, sugar beet, dried, containing less than 30% moisture, reduced to the condition of meal, adapted for indefinite preservation without deterioration, and containing practically the same amount of uninverted sugar as before being dried, substantially as described.

GEORGE WHITMAN McMULLEN.
